COMBINED BUNK BED HEAD BOARD, BLACK-
BOARD AND FOLDING DESK OR SIMILAR ARTICLE

Joseph E. N. Neerincx, Uden, Netherlands, assignor to Diks & Coenen N.V., Uden, Netherlands

Filed Jan. 4, 1971, Ser. No. 103,963

Term of patent 14 years

Int. Cl. D6—01

U.S. Cl. D5—4

FIG. 1

FIG. 2

FIG. 4

FIG. 5

FIG. 1 is a front, top and right side perspective view of a combined bunk bed head board, blackboard and folding desk or similar article, showing my new design with the desk top opened toward the front;

FIG. 2 is a left side, top and rear perspective view with the desk top opened toward the rear;

FIG. 3 is a left side, top and rear perspective view with the desk top folded upward into its storage position;

FIG. 4 is a front elevational view in the storage condition; and

FIG. 5 is a side elevational view in the opened position, the opposite slide being substantially a mirror image thereof.

I claim:

The ornamental design for a combined bunk bed head board, blackboard and folding desk or similar article, as shown and described.
